UNITED STATES PATENT OFFICE.

LEONARD L. MARTIN AND CHARLES R. MAYFIELD, OF KANSAS CITY, MISSOURI, AS-SIGNORS TO AMERICAN ASPHALT ROOF CORPORATION, OF KANSAS CITY, MISSOURI, A CORPORATION OF MISSOURI.

ROOFING SHINGLE.

Application filed January 28, 1924. Serial No. 629,070.

This invention relates to shingles and one of the objects is to produce a shingle of prepared roofing material of such a design that a roof constructed from such shingles will, 5 when viewed edgewise, show up the successive laps of the shingles in three-ply form, thus presenting a layer of roofing of heavier, more substantial, and more attractive appearance than the single-ply prepared roofing now generally used and as 10 usually laid.

Another object is to produce a shingle so constructed that the exposed corners of each shingle can be interlocked with the shingle 15 below to guard against the tearing or ripping loose of the shingles by the force of high winds.

With the objects named in view, the invention consists in certain novel and useful 20 features of construction and organization of parts as hereinafter described and claimed; and in order that it may be fully understood, reference is to be had to the accompanying drawing, in which:—

25 Figure 1 is plan view of a shingle embodying the invention.

Figure 2 is a plan view of a modified form of the invention.

Figure 3 is an edge view to illustrate the 30 appearance of the completed roof.

Figure 4 is a top plan view of a section of roof.

Figure 5 is an enlarged plan view to illustrate the interlocking of the exposed corners 35 of the shingles.

Figure 6 is a section on the line VI—VI of Figure 3.

In the said drawing, where like reference 40 characters identify corresponding parts in all of the figures, 1 represents the rectangular body portion of a shingle embodying the invention. Formed integrally with and projecting from one edge of the body portion are a pair of extensions or tab portions 45 2 and 3, which are of equal width, but the tab portion 3 is twice as long as the tab portion 2. In this connection it is desirable to point out that the tab portions 2 and 3 are formed equal distances from the opposite 50 ends of the body 1 of the shingle to form a pair of shoulders 8 and 9, whose combined widths are equal to the width of either of the tab portions.

The extensions or tab portions 2 are longitudinally slotted at their lower edges 55 as at 4 to form a pair of ears 5. The lower corners of the tab portions 3 are provided with transverse and preferably curved slits 6 to form a pair of ears 7. The slits 6 of each shingle are designed to be engaged and 60 interlocked with the slots 4 of the tab portion 2 of the next underlying shingle 2, with the corresponding ears 7 underlying the ears 5 of said tab portion, as illustrated in Figures 3 to 5.

65 The operation of laying the shingles is as follows:—Referring to Figures 4 and 5, it will be noted that the shingles are laid in horizontal rows, commencing from the bottom edge of the roof, after a suitable plain 70 edge strip (not shown) has first been applied. The shingle A in the first row is secured in position, and the shingle B comprising the next above horizontal row is laid with its extension or tab portion B³ overlying the tab portion A², and having its ears B⁷ engaged through the slots A⁶, thus exposing the ears A⁵ above the ears B⁷, as illustrated. The shoulder portion A⁸ underlies the tab portion B² for one-half of the 75 width of the latter, as shown in dotted lines. The shingles of each successive horizontal row interlock as described, and in Figure 4, the interlocking of a shingle C in the third horizontal row with the shingle B is illustrated. The ears B⁵ are exposed through the slits C⁶, and the slots C⁴ are in position 80 for engagement with the ears 7 of a shingle in the next succeeding horizontal row. The shoulder B⁸ underlies one-half the width of 85 extension or tab portion C², and being abutted by the shoulder X⁹ of the shingle X in the same horizontal row.

90 With the method described of laying a roof, a three-ply or triple thickness roof is produced in the lapped portions thereof which are presented to edgewise view, the exposed corners of the extensions or tab portions of each shingle being interlocked with the shingle below to stiffen the shingle 95 and counteract the tendency of a wind to tear or rip the shingle lose from its fastenings.

100 Considering the successive layers of the shingles of the middle portion of the shingle assembly shown in Figure 3, and starting 105

with the shingle D, the extension or tab portion 3 of this shingle is superposed by the abutting ends of the shingles E and F, the respective edges 8 and 9 of which are left exposed. Overlying these ends of the shingles E and F is the tab portion 2 of the shingle G which is interlocked in the manner above described with the overlying tab portion 3 of the shingle H. Upon this portion 3 of the shingle H are laid the abutting ends 8 and 9 of the shingles I and J, leaving the edges thereof exposed. Upon these end portions of the shingles I and J is placed the tab portion 2 of the shingle K, which in turn is interlocked in underlying relation to the tab portion 3 of the shingle L. In the same superposed relation over this portion 3 of the shingle L are arranged the abutting ends of the shingles M and N, the tab portion 2 of the shingle O and tab portion 3 of the shingle P. Each of the other portions of the roofing, when completely laid, are built up and assembled with all the exposed edges in three-ply formation, and it will be noted that in each instance these three-ply unit portions comprise the parts 8-9, 2 and 3 of the successive shingles, and these several unit portions occur at regular intervals the same distance apart, equal to the length of the tab extension 2. This produces not only the desired effect of thickness and multiple-layer structure, but also an arrangement of ornamental appearance, due to the continuous stepped design obliquely in either direction from the bottom to the peak of the roof.

It will be apparent that the shingles may be nailed in position or secured in any other suitable manner, as common in the art. Figure 2 of the drawing indicates a shingle corresponding in all particulars to the shingle shown in Figure 1, except that it is not provided with the slots 4 and slits 6 produced in the tab corners of the extensions. This type of shingle is secured in position in accordance with the methods above described, except that the corners are not interlocked, although if desirable a locking clip or other fastening device of any desired character may be provided. It is also apparent that the improved type of construction is adapted not only for use as individual units, but may also be embodied in the continuous strip form of roofing.

From the above description, it will be apparent that we have produced a shingle of the character described which possesses all of the features of advantage set forth as desirable, and while we have described the preferred embodiment of the same, we reserve the right to make all changes properly falling within the spirit and scope of the appended claims.

We claim:—

1. A shingle comprising a body portion formed along one of its edges with a plurality of downwardly extending contiguous tab portions of equal width but unequal length, those tab portions adjacent to the ends of the body portion being spaced equal distances from said ends of the body portion. 65

2. A shingle comprising a body portion formed along one of its edges with a plurality of downwardly extending contiguous tab portions of equal width, one of said tab portions being substantially twice the length of another of said tab portions, and those tab portions adjacent to the ends of the body portion being spaced from said ends of the body portion. 70 75

3. A shingle comprising a body portion formed along one of its edges with a plurality of downwardly extending tab portions of unequal length, those tab portions adjacent to the ends of the body portion being spaced from said ends of the body portion, one of said tab portions being provided with means for interlocking with the superimposed tab portion of a second shingle. 80 85 90

4. A shingle comprising a body portion formed along one of its longitudinal edges with a pair of downwardly extending contiguous tab portions of equal width but unequal length and spaced from the ends of the body portion, the combined distances of the tab portions from said ends being equal to the width of each tab portion. 95

5. A roof structure comprising shingles each having a body portion and a plurality of tab portions of unequal length spaced from the ends of the body portion, said shingles being laid in successively stepped and partially overlapping relation and presenting a series of composite tab sections having their free edge portions superposed in three-ply form and the lower edge of each ply exposed flush with the lower edges of the remaining plies, said free edge portions being made up of the adjoining end portions of successive shingles superposed by the shorter and longer tab portions respectively of superposed shingles. 100 105 110

6. A roof structure comprising shingles having body portions and tab portions laid in successively stepped and partially overlapping relation and forming a series of composite tab sections each of three-ply thickness at its lower edge portion and the remaining portions of each tab section being made up of successively fewer plies corresponding substantially to an upwardly tapered shingle. 115 120

In witness whereof we hereunto affix our signatures.
